Primary Examiner — Leanne Was-Englehart

(57) **CLAIM**

The ornamental design for a rescue balloon device as shown and described.

DESCRIPTION

Fig. 1.1 is a front view of the rescue balloon device.
Fig. 1.2 is a front-left side view of the rescue balloon device.

Fig. 1.3 is a left side view of the rescue balloon device.

Fig. 1.4 is a rear view of the rescue balloon device.

Fig. 1.5 is a right side view of the rescue balloon device.

Fig. 1.6 is a front-right side view of the rescue balloon device.

Fig. 1.7 is a top view of the rescue balloon device.

Fig. 1.8 is a bottom view of the rescue balloon device.

The equal-length broken lines in the reproductions depict portions of the rescue balloon device that form no part of the claimed design. The "AirMarker" lettering and icon shown in broken lines is a registered trademark of AirMarker AG.

1 Claim, 8 Drawing Sheets
